SPLASH GUARD FOR MOTOR VEHICLES

Robert Podall, Highland Park, Ill., assignor to Jeffrey-
Allan Industries, Inc., Chicago, Ill., a corporation of Illinois

Filed May 6, 1966, Ser. No. 2,197

Term of patent 14 years

(Cl. D14—6)

FIG. 1 is a perspective view of a splash guard for motor vehicles embodying the design; and

FIG. 2 is a sectional view on an enlarged scale taken substantially as indicated along line 2—2 of FIG. 1.

The side opposite that shown is substantially plain.
I claim:

The ornamental design for a splash guard for motor vehicles, as shown and described.
